UNITED STATES PATENT OFFICE

JOHN H. IRWIN, OF MORTON, PENNSYLVANIA.

TELEPHONE.

SPECIFICATION forming part of Letters Patent No. 430,128, dated June 17, 1890.

Application filed April 24, 1880. Serial No. 8,323. (No model.)

To all whom it may concern:

Be it known that I, JOHN H. IRWIN, of Morton, in the county of Delaware and State of Pennsylvania, have invented a new and useful Improvement in Telephones, whereof the following is a full and exact description.

This invention relates to that class of telephones wherein there is a diaphragm which bears one electrode and has another electrode held in contact therewith; and it consists in mounting said second electrode upon an adjustable elastic weighted arm, which is free at one end and insulated as to said diaphragm and its electrode.

It is to be understood that the instrument herein shown is designed for use as a transmitter in any ordinary telephonic circuit, and any proper telephonic receiver may be employed therewith.

That others may fully understand my invention, I will particularly describe it, having reference to the accompanying drawings, wherein—

Figure 1 represents my invention in sectional perspective. Fig. 2 is an enlarged elevation of the electrode and diaphragm.

The transmitter B is composed of an electrode *h*, provided with a contact-surface of platinum or other suitable material mounted upon the end of an elastic reed *i*, and weighted at the free end, as shown at *k*. The reed is fixed at its rear end and the electrode *h* is put in the circuit by elastic connection with said reed if the same is composed of a conducting material, or by a separate conductor if the reed is composed of a non-conducting material. The elasticity of the reed *i* tends to lift the electrode, and the superimposed weight *k* is sufficient to overcome the elasticity of the reed and maintain the proper contact of the electrodes. This contact is therefore the effect of the constant and unvarying force of gravity, and the counteracting force of the spring is a differential quantity, capable of the most delicate adjustment by regulating the adjusting-screw *p* or other proper means for securing the proper initial pressure. The electrode *h* is in contact with the electrode *t*, which is preferably formed of gas-carbon mounted upon a receiver of sound-waves or diaphragm *m*. The fixed end of the reed *i* is also secured to the surface of the dia-

phragm *m*, and therefore no disturbance of relation between the electrodes will then occur if the diaphragm *m* shall from any cause become displaced more or less upon its support. 55

It is necessary to interpose between the fixed end of the reed and its support upon the diaphragm *m* a cushion of some non-conducting substance like india-rubber, which is also elastic and has great power to absorb vibrations. I therefore mount the fixed end of the reed *i* upon a block of india-rubber *n*, 65 and secure it there by a bolt *p*, which passes downward through the reed, block *n*, and diaphragm *m* into a nut or other fastening.

All matters originally shown and described in this application, excepting that relating specifically to the mounting of both electrodes upon the diaphragm, are disclaimed, because they form the subject of another patent. 70

Having described my invention, what I claim as new is— 75

1. In a telephone-transmitter, a diaphragm having both electrodes mounted upon it, one electrode being mounted directly upon such diaphragm and the other electrode being secured to an elastic arm mounted upon said diaphragm, substantially as described. 80

2. In a telephone-transmitter, a diaphragm having both electrodes mounted upon it, one electrode of carbon being mounted directly upon such diaphragm and the other electrode being secured to an elastic arm mounted upon a block fastened to said diaphragm, substantially as described. 85

3. In a telephone-transmitter, the combination, with a diaphragm carrying one electrode, of an insulating-block fastened on said diaphragm and moving with the same, and carrying an elastic arm bearing the other electrode, the tension of said arm being opposed by a weight on the same, substantially 90 as set forth.

4. In a telephone-transmitter, an insulating-block secured to the diaphragm and carrying an elastic arm, to which is secured an electrode maintained in contact with another electrode mounted directly upon the diaphragm. 100

J. H. IRWIN.
